UNITED STATES PATENT OFFICE.

ALEXANDER WINTON AND HAROLD B. ANDERSON, OF CLEVELAND, OHIO, ASSIGNEES
TO THE WINTON MOTOR CARRIAGE COMPANY, OF CLEVELAND, OHIO.

STARTING MECHANISM FOR EXPLOSIVE-ENGINES.

8,116,131.

Specification of Letters Patent.

Patented Nov. 3, 1914.

Application filed August 15, 1906. Serial No. 330,714.

To all whom it may concern:

Be it known that we, ALEXANDER WINTON and HAROLD B. ANDERSON, citizens of the United States, residing at Cleveland, in the county of Cuyahoga and State of Ohio, have invented certain new and useful Improvements in Starting Mechanism for Explosive-Engines, of which the following is a specification, reference being had therein 10 to the accompanying drawing.

This invention relates to improvements in starting mechanism for explosive engines, the object of which is to charge the cylinders of an engine with explosive charges 15 without "cranking" it for that purpose, and the charge in the proper cylinder can be ignited by the igniting mechanism used in running the engine, and the engine thereby started without cranking.

20 In the accompanying drawings, Figure 1, is a view showing the invention applied to a multiple cylinder explosive engine, mounted on an automobile, the engine being shown in side elevation. Fig. 2, is a top plan view 25 of the same. Fig. 3, is a sectional view through one of the cylinders of the engine. Fig. 4, is an enlarged view of the cock through which the cylinders are charged. Fig. 5, is an enlarged view of the cock for 30 connecting the cylinders with the atmosphere.

Referring now to the drawings, 1 is a view of any desired form of multiple cylinder explosive engine. The engine here 35 shown has four cylinders, and as here shown, is of the vertical cylinder type.

This invention has relation to explosive engines for driving vehicles, and as here shown, is located in front of the dash-board 40 2. The cylinders of the engine are connected up with the usual carbureter 3, through which they are charged when the engine is running, and is so well understood by those skilled in the art that further illustration 45 and description are not necessary for the purpose of explaining the present invention.

The engine cylinders are here shown provided with charging cocks 4, and in the arrangement here shown these cocks form 50 charging openings independent of the openings through which the cylinders are charged when the engine is running. These cocks are connected by pipes 5 to a device 6 for forcing an explosive charge into the cylinders through the said cocks. The form

of forcing device here shown is a hand-operated pump, but this may be a different device, as will be described hereinafter. This pump, or forcing device 6 is connected with any desired or suitable form of carbureter 7.

The cocks 4 are provided with arms 8 by means of which they are opened and closed, and these arms are connected by a rod 9, so that they may be operated together.

65 Each of the engine cylinders is provided with cocks 10 for connecting them with the atmosphere during the hand-charging operation for a purpose to be explained presently. These cocks are provided with arms 11 by means of which they can be opened and closed, and these arms are connected by a rod 12 so they can be operated together. The rods 9 and 12 are connected to a member 13 so that the cocks 4 and 10 can all be 70 opened and all closed at the same time and by a single member, though such arrangement is not essential to the invention. The member 13 here shown is intermediately pivoted at the point 14 and has an operating 75 handle 15 extending through the vehicle dash-board 2 for convenience in operating. When the handle 15 is moved in one direction, all the cocks are opened, and when moved in the other direction, all are closed. 80 Also for convenience in operation, the pump 6 is located back of the dash-board 2.

85 It is well known by persons skilled in the art that multiple cylinder engines stop with one at least of the pistons in position for 90 the power stroke, and such engines can therefore often be started when hot by working the sparking lever or switch. This manner of starting, however, is well known to be very unreliable for many reasons, among 95 which is sufficient to mention the loss of the charge by leakage past the valves, and piston, and the sucking into the cylinder uncarbureted air caused by the cooling of the cylinders. In starting an explosive engine by an arrangement involving the invention here disclosed, all the cocks 4 and 10 are opened. Carbureted air is then forced 100 through the carbureter 7 into the cylinders; the cocks closed, and the engine can be 105 started by the switch or sparking lever.

This invention has been found in practice to be thoroughly reliable, for it furnishes a charge of the proper mixture of air and gasoline to be ignited when the spark is 110

produced, and it charges all the cylinders, so that the particular cylinder in which the piston is on its power stroke, and in which the spark will occur when the switch is turned on, is sure to be charged, and also the other cylinders for the succeeding explosions, and the cylinder in which the first explosion occurred is thereafter charged from the running carbureter 3.

10 The reason for connecting the cylinders with the atmosphere during the charging operation is, that some of the cylinders will stop with the inlet or exhaust valve thereof open, thus connecting them with the atmosphere, and it is necessary to connect the other cylinders with the atmosphere also, for otherwise they could not be charged, since the mixture would take the line of least resistance and pass to the atmosphere.

15 through the open valves, and would not enter the cylinders which were closed to the atmosphere. It is the cylinder that has its valves closed that must be charged, for it is the cylinder which is on its power stroke,

20 and in which the spark will occur when the switch is turned on. To assist in insuring the igniting of the charge thus forced into the cylinders, the charging cocks are placed close to, and preferably over the sparking

25 30 plugs 16, as shown in Fig. 3. Instead of having a hand pump as 6, a chamber carrying compressed air could be provided, and the air forced through the carbureter to the cylinders. The said chamber could in such

35 event be provided with compressed air by means of a pump operated by the engine. As before stated, the essential broad idea of the invention is to charge the cylinders of the engine independent of the engine piston suction, so the engine can be charged without cranking.

The spark is controlled by a lever or handle 17, the operation of which is well understood by automobile drivers and others skilled in the art, and needs no further illus-

Having thus described the invention, the following is claimed and desired to be secured by Letters Patent:

1. The combination with a multiple cylinder explosion engine, engine operated means for supplying the explosive mixture thereto, and an engine operated igniting mechanism, of a carbureter and a hand-operated air suction and compression device having a suction communication with the carbureter for supplying an explosive mixture simultaneously into all the cylinders, and an air outlet in direct communication with the explosion chamber of the engine independent of the exhaust outlet, and a hand operated spark controlling device to cause a spark in the cylinder when the engine is at rest.

2. The combination with a multiplecylinder explosion engine, engine operated means for

supplying an explosive mixture to the cylinder, an engine operated ignition mechanism for the cylinder, of a carbureter, a hand pump located between the carbureter and the cylinder for supplying an explosive mixture simultaneously into all the cylinders, the pump having a suction communication with the carbureter and an air outlet in direct communication with the engine cylinder independent of the exhaust outlet, and a hand operated device for causing said 75 sparking mechanism to ignite the hand supplied explosive charge in the cylinder while the engine is at rest.

3. The combination of a multiple cylinder explosive engine, means operated by the engine for a normal supply of explosive mixture to the cylinders, an engine operated ignition mechanism for the cylinders, a carbureter, connections between the carbureter and said cylinders, an air supply device connected with the carbureter to force an explosive mixture simultaneously into all of the cylinders, each cylinder having a controlled atmospheric communication independent of the exhaust outlet, hand operated means for simultaneously opening and closing said communications, an ignition device for each cylinder, and a hand operated device common to and adapted to operate said last ignition devices. 95

4. The combination of a multiple cylinder explosive engine, means operated by the engine for a normal supply of explosive mixture to the cylinders, an engine operated ignition mechanism for the cylinders, each cylinder having a manually controlled atmospheric communication independent of the exhaust outlet for the purpose described, means for charging the cylinders with an explosive mixture while the engine is at rest, an ignition device for each cylinder, and a hand-operated means common to and adapted to operate the said ignition mechanism when the engine is at rest. 100 105

5. The combination of a multiple cylinder explosive engine, means operated by the engine for a normal supply of explosive mixture to the cylinders, an engine operated ignition mechanism for the cylinders, each cylinder having a combined manual means for controlling the atmospheric communication independent of the exhaust outlet, and for charging the cylinders with an explosive mixture while the engine is at rest, an ignition device for each cylinder and a hand operated means common to and adapted to operate the said ignition mechanism when the engine is at rest. 110 115 120

6. The combination of a multiple cylinder explosive engine, means operated by the engine for a normal supply of explosive mixture to the cylinders, an engine operated ignition mechanism for the cylinders, a car- 125

bureter independent and separate from the normal explosive mixture supply, connections between the said carbureter and the cylinders, an air supply device connected 5 with the carbureter to force an explosive mixture simultaneously into all of the cylinders, each cylinder having a controlled atmospheric communication independent of the exhaust outlet, hand operated means for 10 simultaneously opening and closing said communications, an ignition device for each

cylinder, and a hand operated device common to and adapted to operate said last ignition device.

In testimony whereof we affix our signatures in presence of two witnesses. 15
